M. J. LEWIS

CIRCULATING TOOL JOINT FOR CORE BARRELS AND THE LIKE

Filed Nov. 27, 1922

UNITED STATES PATENT OFFICE.

MILES J. LEWIS, OF LONG BEACH, CALIFORNIA.

CIRCULATING TOOL JOINT FOR CORE BARRELS AND THE LIKE.

Application filed November 27, 1922. Serial No. 603,621.

To all whom it may concern:

Be it known that I, MILES J. LEWIS, a citizen of the United States, residing at Long Beach, in the county of Los Angeles and State of California, have invented a new and useful Circulating Tool Joint for Core Barrels and the like, of which the following is a specification.

Ordinarily, in the taking of samples of the strata through which a well is being bored, the core barrel is inserted in the well and, before it strikes the hard un-drilled formation at the bottom, it passes through considerable liquid and detritus dislodged by the drilling operation. The bore of the core barrel thus tends to become packed with detritus. When the core barrel reaches the hard formation it is rotated to cause it to penetrate said formation, but the detritus already lodged in the core barrel will, to a more or less degree, prevent the core of solid formation filling the core barrel. In other words, when the driller has withdrawn the core barrel from the well, after supposedly obtaining a core representative of the formation at the bottom of the well, he cannot tell for a certainty whether or not the core he has taken is representative of the stratum at the bottom or of the strata higher up.

An object of this invention is to make it possible to obtain a core that, with certainty, will be known to contain only the hard formation at the bottom of the well hole being drilled.

Another object is to provide for continuous flushing of the core barrel with the fluid until the core barrel strikes the bottom of the hole, and then to shut off the flushing fluid from the core barrel.

The accompanying drawings illustrate the invention:

Figure 1 is a vertical mid section of a tool joint constructed in accordance with the provisions of this invention, the relatively rotatable members thereof being in position to shut off the flow of fluid into the upper end of the core barrel which is adapted to be connected with the lower end of said tool joint.

Fig. 2 is a plan view of the upper end of Figure 1.

Figs. 3 and 4 are plan sections on the lines indicated by 3-3 and 4-4, respectively, Figure 1. In Figure 4 the relatively rotatable members are in the positions they

occupy to admit the flushing fluid to flow through the tool joint and into the core barrel that may be attached thereto.

Fig. 5 is a reduced plan section on the line indicated by 5-5, Figure 1.

Figure 6 is an inverted plan view of the lower end of the outer member.

Figure 7 is a reduced section of the inner member on the line indicated by 7-7, Fig. 1.

Figure 8 is a reduced longitudinal view of the tool joint coupled with a core barrel.

The tool joint comprises an outer member 11 and an inner member 12. The outer member 11 is provided at its upper end with coupling means in the form of a pin 13 adapted to engage the drill collar of the drill pipe line, not shown. The lower end of the inner member 12 is provided with coupling means in the form of a box 14 adapted to cooperate with the pin of a core barrel so that the core barrel may be connected with the tool joint. The core barrel is indicated at *a* in Fig. 8, and may be of any suitable construction. The box 14 and pin 13 may be of the usual box and pin construction employed on oil well tools.

The outer member 11 is provided with an internal screw-thread 15 which engages an external screw-thread 16 on the inner member 12. These are preferably relatively coarse threads.

The upper end of the inner member 12 constitutes a two-way valve indicated at 17. The valve 17 is provided with a longitudinally extending port or ports 18 and with another port or ports 19 extending from the upper end face of the valve to the periphery thereof, as clearly seen in Figure 1. The ports 18, 19 are positioned at ninety degrees of circular measurement from one another so that, when the valve 17 is turned to the position shown in Figure 1, the ports 19 will register with ports 20 extending through the pin 13 and with laterally extending ports 21 extending from the interior of the member 11 to the peripheral face thereof. Also, when the valve 17 is turned to position ninety degrees of circular measurement from the position shown in Figure 1, or to the position shown in Figure 4, the ports 18 will register with the ports 20. Thus, in this position of the valve 17, the ports 19 will be closed and the ports 18 opened.

When the valve 17 is in position to register the ports 19 with the ports 20, 21, a shoulder

22 on the lower end of the outer member 11 is in engagement with a shoulder 23 on the outer member 12 and, when these shoulders are thus engaged, preferably the upper 5 end of the valve 17 will be slightly spaced from the upper end of the bore 24 of the outer member, thus enabling the inner and outer members to be relatively turned to easily unscrew them. The shoulders 22, 23 10 are constructed to engage when the members 11, 12 are relatively turned to screw the inner member into the outer member and to permit unscrewing thereof. These shoulders 22, 23, are merely for the purpose of 15 preventing frictional engagement of the upper end of the valve 17 with the upper end of the bore 24 and, of course, could be dispensed with if so desired.

When the members 11, 12 are turned to 20 position with the shoulders 22, 23 in engagement, as in Figure 1, a latch plunger 25 projects from a socket 26 in the member 12 into a socket 27 in the member 11, a coil spring 28 in the socket 26 tending to urge 25 the plunger 25 outwardly.

When the members 11, 12 are in the relative positions shown in Figure 4, a radially extending hole 29 in the outer member 11 registers with a radially extending hole 30 30 in the inner member 12. When the members 11, 12 are thus positioned, a pin 31, shown in Figure 4, is inserted in the holes 29, 30 and prevents relative rotation between the members 11, 12, unless torque of 35 the member 11 and resistance thereto of the member 12 effects shearing of said pin, as will be explained more fully hereinafter. Of course, when the pin 31 is in position, the plunger 25 will be compressed within 40 the socket 26 and will be positioned ninety degrees of circular measurement from the socket 27, as clearly shown in Figure 4.

The main details of construction of the tool joint have been described above, but 45 certain other features of construction, though not necessary, are preferable, and they will now be described. Preferably the valve 17 is constructed of three separate members, an externally threaded member 32, 50 an internally threaded body 33 screwed on to the member 32 and of less length than the member 32, and a third member 34 internally threaded to engage the member 32. The body 33 is provided in its peripheral face adjacent its lower end with 55 an annular groove 35 in which is seated a packing ring 36, preferably of rubber or the like. Also the member 34 is provided in its peripheral face adjacent its lower 60 end with an annular groove 37 in which is seated a packing ring 38 of rubber or the like. The packing ring 36, 38 insure against leakage of fluid between the valve and the peripheral wall of the bore 34, and 65 the construction of the valve in pieces, as

described, is merely for the purpose of facilitating the emplacement and removal of the packing rings.

Some core barrels are provided with vents or ports near their upper ends, as indicated at *b* in Fig. 8, to permit ejection of fluids from the interior of the core barrel as the core moves inwardly in the bore of the core barrel. When such core barrels are connected with this tool joint, it is not absolutely necessary to provide vents in the member 12. However, since it may be advisable or even necessary to employ such vents, I have provided them as indicated at *b*. The vents *b* open at their lower ends into the bore 40 of the inner member 12 and open at their upper ends at the peripheral face of the valve 17. When the members 11, 12 are in position to register the ports 19 with the ports 20, 21, the vents *b* register with radial ports 41 opening from the bore 24 of the member 11 to the peripheral face of the member 11.

The tool joint described above with the pin 31 in place, as in Fig. 4, operates as follows: The core barrel, indicated at *a* in Fig. 8, to be employed in obtaining the test core is connected with the box 14 and the pin 13 is connected with the drill pipe collar, in a manner readily understood. The tool joint with the core barrel attached thereto is then lowered into the well hole and, while it is being lowered through the fluid, detritus and other loose material in the well, a fluid will be pumped through the drill pipe the same as when boring the well. This fluid passes through the ports 20, 18, into the bore 40 and thence into and through the bore of the core barrel and discharges at the lower end of said core barrel. The fluid thus discharging flows upwardly around the periphery of the core barrel, preventing the detritus and other loose material adjacent said core barrel from packing and entering said core barrel. Because of the detritus being loosened and carried away as the core barrel descends, there is no material resistance to descent of the core barrel until the lower end thereof engages the hard formation from which the core is to be taken. As soon as the core barrel strikes the hard formation, the drill pipe line will be rotated, in a manner well understood in this art, to effect penetration of the core barrel into said formation. The core barrel meets with resistance to its rotation and the torque of the member 11 against such resistance causes shearing of the pin 31, thus permitting the outer member 11 to rotate a quarter of a turn, or until the shoulder 23 engages the shoulder 22, as in Figure 1. This, as has been explained above, effects closing of the ports 18 and opening of the ports 19 so that the supply of fluid is shut off from the inner

member 12 and core barrel and the fluid discharges instead through the ports 21, thus continuing to carry away from the periphery of the tool joint and core barrel the detritus 5 surrounding the same. As the core barrel penetrates deeper and deeper into the formation, the fluids that may be in the bore 40 are readily discharged therefrom through the vent 39 and ports 41 by reason of the 10 tendency of the core to compress the fluids as it advances into the bore of the core barrel.

When, in the judgment of the operator, the core barrel has been caused to penetrate 15 sufficiently far into the formation to obtain a solid core throughout substantially the full length of the core barrel, the drill pipe will be elevated to withdraw the core barrel from the hole made thereby. This withdrawing operation, because of engagement 20 from time to time of the member 12 with the wall of the well, might tend to unscrew the member 12 from the member 11 were it not that, when the shoulder 23 engaged the shoulder 22, the plunger 25 came into registration with the socket 27 and was thrust 25 into said socket by the expansive force of the spring 28. Of course this plunger 25 positively prevents unscrewing of the member 30 11 from the member 12. It is to be understood that it may not be absolutely necessary to provide the plunger 25 and sockets 26, 27, since the screw-threads 15, 16 may produce sufficient friction to prevent the unscrewing movement mentioned above, how- 35 ever, it is preferable that some such latching means as the plunger 25 be employed so

as to absolutely insure against such unscrewing.

It is preferable that the core barrel be 40 without the vent b, so that all of the fluid forced into the upper end of the core barrel will flow to the lower end thereof.

I claim:

1. In a method of obtaining a test core 45 from a well, the combination of steps consisting in forcing a flushing fluid through the core barrel while lowering said core barrel into engagement with the formation from which the core is to be taken, and then 50 while the core barrel is adjacent to the formation shutting off the flushing fluid from the core barrel and forcing the core barrel into the formation.

2. The combination with a core barrel, of 55 means to admit a flushing fluid to the upper end of the core barrel while said barrel is being lowered into contact with the formation at the bottom of the well hole, said means being operable by resistance of the 60 core barrel to rotation to shut off the flow of fluid to the core barrel.

3. In a tool joint, the combination of 65 valved means to admit a flushing fluid to the upper end of a core barrel while said core barrel is being lowered into contact with the formation at the bottom of the well hole, said means being operated to shut off the 70 flow of fluid to the core barrel by resistance of the core barrel to rotation when said core barrel engages said formation.

Signed at Los Angeles, California, this 20th day of November, 1922.

MILES J. LEWIS.
